PLASTIC SHEET MATERIAL

John R. Ellefson, Newburgh, N.Y., assignor to E. I. du
Pont de Nemours and Company, Wilmington, Del., a
corporation of Delaware

Application November 17, 1958, Serial No. 53,398

Term of patent 14 years

(Cl. D87—3)

FIG. 1

FIG. 2

FIG. 3

Figure 1 is a plan view of a plastic sheet material showing my new design. Figure 2 is an enlarged portion of the design shown in Figure 1. Figure 3 is a cross-sectional view taken on line 3—3 of Figure 2.

I claim:

The ornamental design for a plastic sheet material, substantially as shown.
